UNITED STATES PATENT OFFICE

MICHAEL J. McINTYRE, OF EDEN CENTER, NEW YORK

SAFETY GUARD FOR MACHINES

Application filed August 4, 1928. Serial No. 297,420.

This invention relates to improvements in safety guards for machines, and particularly to machines which are fed by hand and caused to be operated intermittently at the will of the operator.

Safety guards as made at present are principally of two types, those of a stationary and permanent character which surround the stationary and movable die so that an operator's hand or fingers cannot be inserted between them but allow of the insertion of a sheet of metal through or beneath said guard, and those of a movable character which sweep the operator's hand away from the danger zone when the movable die starts to approach the stationary die.

The stationary type of guard gives complete protection to the operator so he has no chance to get injured by inadvertently inserting any portion of his hand between the dies when they are coming together. The common movable type of guard gives protection when the operator places his hand in front of it to insert a piece of material between the dies as the guard then sweeps his hand away as soon as the movable die starts to approach the stationary die. But it does not give complete protection as the operator can insert his hand back of the guard or around it outside of its sweep.

Operators are instructed in the proper way to operate a machine so the guard will protect them and to use a stick to push away scraps from the dies, but when they are doing piece work they get careless and try to avoid the guard which in this type they can do by reaching around it.

The objects of this invention are:

First, to provide a safety guard for punch and forming presses or other machines which combine the advantages of the stationary and movable types by enclosing the danger zone and providing a suitable opening for the operator, said opening protected by a movable portion to sweep his hand away when the movable die starts to approach the stationary die.

Second, to provide a guard for machines of the class described which is adapted to be mounted thereon as an attachment and which

is adjustable to accommodate different sizes and makes of machines and different working conditions.

Third, to provide a guard for machines of the class described having a movable portion to sweep an operator's hand from the danger zone and stationary portions to prevent said operator's hand reaching said danger zone outside of the sweep of said movable portion.

Fourth, to provide a guard for machines of the class described having a movable portion to sweep an operator's hand from the danger zone and geared to the movable die head to give an increased movement and speed over said die head movement and speed.

Fifth, to provide a guard for machines of the class described having a movable portion to sweep an operator's hand from the danger zone and means to prevent said operator's hand reaching said danger zone outside of the sweep of said movable portion, one part of said means being locked until the movable die starts to approach the stationary die when said part of said means is unlocked to allow removal of operator's hand from the danger zone.

With these objects in view, the invention consists in certain features of novelty in the construction, combination and arrangement of parts by which the said objects and certain other objects which will hereinafter appear are attained, the invention being more particularly pointed out in the claims.

My guard device then combines stationary and movable guard means consisting of a stationary fixed portion, a swinging movable portion which may be locked in its closed position and a reciprocating movable portion.

In the drawings accompanying and forming a part of this specification.

Figure 1 is a front elevation of a portion of a punch press equipped with my improved guard, the punch press being shown mainly in conventional form with the movable die head in its upper position and the guard in its open position.

Fig. 2 is a side elevation of a portion of

a punch press showing one side elevation of my improved guard.

Fig. 3 is a top view or plan of my improved guard attached to the punch press, a portion of said press being in section on line 3—3 of Fig. 1 and a portion of the stationary guard in section on line 3 of Fig. 1. The front of said guard is in its closed position.

Fig. 4 is a front elevation of my improved guard mounted and showing a portion of a punch press with its movable die head and die in its lower position and the front of said guard in its corresponding closed position.

Fig. 5 is a partial section on line 5—5 of Fig. 2 to show a modification of locking means for the swing guard.

Figs. 1 and 2 show the press and guard in the so-called open position ready to receive a piece of material and Figs. 3 and 4 show the press and guard in its so-called closed position when the dies are together after having acted upon a piece of material.

Referring to the drawings, 1 indicates a punch press generally in conventional form and having a bed 2 on which a stationary or lower die 3 is mounted in the usual manner. 4 is an upper die which acts in conjunction with lower die 3 to punch or form a piece of material. Upper die 4 is mounted in the reciprocating die head 5 which latter acts to move the former toward and away from stationary die 3. 6 is a connecting rod to actuate the die head 5 from the crankshaft 7.

The punch press has the usual trip (not shown) to be pressed by the operator's foot when a piece of material is in place on the lower die. The upper die then starting from its upper position shown in Fig. 1 descends to its dotted position a distance represented by 51, which is the same lower position shown in Fig. 4, and returns to the upper position when it again comes to rest. This operation is repeated for each piece of material inserted between the dies but as the punch press is a conventional type further description of its operating mechanism is deemed unnecessary as it forms no part of my invention.

9 is a guide having slots 10 for fastening to the front edge of bed 2 and having a groove 11 shaped like an inverted T (Fig. 2) to form a way in which the foot 12 of the movable guard 8 is reciprocated. 13 is a strip fastened to the top of guide 9 to form one portion of the way and as a convenient means of easily finishing said way 11. A portion of the guide 9 projects over and rests on the top of bed 2 shown in the end view of said guide in Fig. 2. At one end of, and as a portion of guide 9 is a vertical lug 14 which forms a support for the shaft 15. A lever 16 is formed integral with the shaft 15

on one of its ends and integral with a pin 17 on its other end.

The reciprocating guard 8 has a boss 18 with three holes 19 to operatively connect it with the lever 16 by means of the link 20. The link 20 has a boss 21 on one of its ends with a suitable hole in which the pin 17 partly rotates and a pin 22 on its other end which partly rotates in one of the holes 19. The said holes 19 are for the purpose of adjusting the travel of the guard 8 and for different sized machines. At the rear of lug 14 is a pinion 23 fastened on the end of shaft 15 by means of a screw 24 which also acts as a key to drive said shaft 15.

Fastened to the front of the die head 5 is a horizontal arm 25 on one end of which is fastened a rack 26 by means of a bolt 27 passing through a slot 28 in rack 26. Slot 28 is for adjusting the position of said rack 26 on said arm 25, and 23 is wider than 26 for adjustment and wear.

Fastened to the left side of the machine 1 (Fig. 1) is a vertical bracket 29 slotted for vertical adjustment, and having a foot 30 with a vertical pivot pin 31 on which is mounted a guard 32 adapted to swing on said pin 31. An adjustable stop screw 33 in the swing guard 32 abutting against vertical bracket 29 determines the closed position of said swing guard 32 and a spring 34 yieldingly holds said swing guard in its closed position.

35 is a rod adjustably fastened on the end of arm 25 and passing through a rectangular opening 36 in the swing guard 32. Slightly above said opening 36 is a block 37 on the outside of swing guard 32 for limiting the upward adjustment of a pin 38 in the rod 35. 38 is a pin vertically adjustable through said rod 35 and adapted to project above the upper edge of said opening 36 a distance 47 to lock said swing guard in its closed position. On the inside of swing guard 32 is a block 39 having an inclined lower surface 45 as shown for the purpose of raising said swing guard 32 to allow pin 38 to pass through opening 36 in case the die head 5 and with it the arm 25 returns to its upper position before said guard 32 has swung closed.

On the right side of machine 1 (Fig. 1) and opposite to the swing guard 32 is a stationary guard 40 having a vertical portion fastened to the lug 14 by screws 41 and a horizontal portion fastened to the frame of the machine 1 by screws 42. In Fig. 3 the upper portion of guard 40 is cut away on the section line 3 of Fig. 4 but its shape is shown in dotted lines. The stationary guard 40 is to prevent an operator from reaching around to the right and back of the reciprocating guard 8 or over the top of it into the danger zone. The swing guard 32 is to prevent an operator from reaching around to the left outside of the travel of the reciprocating front guard and into the danger zone. On machines where there is

not sufficient space between the guard 8 and the front of the machine 1 for an operator's hand, the horizontal part of guard 40 can be omitted.

- 5 The front vertical edge of guard 8 has an enlarged circular section 43 to accommodate a split piece of rubber hose 44 to act as a bumper to contact with the operator's hand in sweeping it aside.
- 10 Fig. 1 shows the positions of the dies and guards when ready to receive a piece of material to be operated upon. The operator then places a piece of material on the lower die 3 and withdraws his hand and trips the machine. As the die head 5 descends bringing the dies 4 and 3 together it carries downward the arm 25 and its rack 26, rotating the pinion 23 and shaft 15 to reciprocate the guard 8 to the position 8' (Fig. 1) by means of the lever 16 and link 20. In Fig. 1 when the guard 8 is at the forward end of its travel as indicated by 8' the lever 16 is in position 16' and link 20 in position 20', the pin 17 having described an arc 46. In Fig. 4 this forward position of guard 8 is shown with the die 4 in its lower position. When die head 5 returns from position Fig. 4 to position Fig. 1 the direction of rotation of pinion 23 is reversed as rack 26 travels upward and the guard 8 is returned to position of Fig. 1. As soon as die head 5 has descended a distance 47 (which is the distance the top of pin 38 is adjusted above the top edge of rectangular opening 36) the swing guard 32 is free to be swung open. In case the operator's hand is in the danger zone it is swept aside to the left by the closing of the reciprocating guard 8, and if his hand is swept far enough to the left to contact with the swing guard 32, said swing guard 32 opens to a position represented by 32' (Fig. 3) and closed again under the action of spring 34.

Referring to Fig. 1, 51 is the distance traveled by the die 4 and at the same time the bumper 44 moves to 44' a distance of 52, so that an operator's hand is moved out of the danger zone at a greater speed than the movement of die 4. A longer movement 52 in proportion to movement 51 and so a greater proportionate speed can be accomplished by gearing up the connecting parts between the die 4 and the guard 8.

When operating the press 1 steadily and as rapidly as consistent with inserting pieces between the dies 3 and 4 the safety feature of this guard is to compel the operator to use only the opening into the danger zone which is protected by the reciprocating guard 8 and so prevent the operator from reaching around said guard 8 as a quick means of displacing a piece of scrap or for any other reason. The operator gets in the habit of inserting pieces of material and tripping the machine regularly and in trying to keep up this regularity

he is liable to get injured if he can reach around a safety guard which sweeps across the front.

The operator can raise swing guard 32 to clear pin 38 and swing it out, if necessary, but in so doing he has stopped operations and is not so liable to be injured by inadvertently tripping the machine.

A different form of lock is shown in Fig. 5 for said swing guard 32 consisting of a concealed spring catch 48 as a part of the rod 35 in place of the pin 38 when the swing guard 32 can only be opened by loosening the set screw 49 which projects into the groove 50 on pivot pin 31 and then raising said guard 32 to clear said catch 48.

Having thus described my invention, what I claim as new and desire to secure by Letters Patent, is:

1. The combination with a machine having a stationary and a movable die, an actuated member to carry said movable die, a crank-shaft and a connecting rod to operate said actuated member, of a guard to sweep in front of the danger zone between said dies, means to operatively connect said actuated member and said front guard and means to guard the openings to the danger zone not swept by said front guard, said latter guard means including a movable guard and a lock to hold said movable guard locked in its closed position only during the rest period of said actuated member.

2. The combination with a machine, including a frame, an actuated member, a crank-shaft and a connecting rod therefor, of a reciprocating guard to sweep in front of the danger zone of said machine, means to operatively connect said actuated member and said reciprocating guard, fixed guard means to close the danger zone back of and above said reciprocating guard, a swing guard at the side of said danger zone and means connected to said actuated member to lock said swing guard stationary in its closed position and unlock said swing guard by the movement of said actuated member.

3. The combination with a machine, including a frame, an actuated member and movable means on said machine to actuate said member, of a guide mounted on the front of said machine for horizontal adjustment, a guard mounted in said guide and adapted to be reciprocated in front of said actuated member, means to operatively connect said guard and said movable means on said machine to reciprocate said guard, a fixed guard at one side of said actuated member, a movable guard at the other side of said actuated member and movable only during the reciprocation of said front guard and a bracket mounted on said machine for vertical adjustment to support said swing guard.

4. The combination with a machine, including a frame, an actuated member and

movable means on said machine to actuate said member, of a guard to reciprocate in front of said actuated member, means to operatively connect said guard and said movable means on said machine to reciprocate said guard, a swing guard at one side of said actuated member, a spring to move and yieldingly hold said swing guard in a closed position and means to lock said swing guard in its closed position when said actuated member is in its upper position and adapted to unlock said swing guard when said actuated member has started to descend.

5. The combination with a machine, including a frame, an actuated member and movable means on said machine to actuate said member, of a guide mounted on said machine, a guard mounted and adapted to be positively reciprocated a fixed distance in said guide, a boss on said guard with holes for adjustment of the travel of said guard and means to operatively connect said actuated member and said guard, said means including respectively a rack and a meshing pinion, 25 a lever fastened to said pinion, and a link connected between said lever and said guard, said rack and pinion having different widths of face for adjustment and wear.

6. The combination with a machine, including a frame, an actuated member and means to actuate said member, of guard means to effectively enclose the danger zone to said actuated member, said guard means including a fixed guard at one side of said danger zone, a fixed guard above said danger zone, a movable guard adapted to pass in front of said danger zone and a side movable guard opposite said fixed side guard, means to operatively connect said movable front guard 40 and said actuated member and locking means connected to said actuated member to lock said side movable guard during the rest period of said actuated member and release said side movable guard by the movement of said actuated member.

7. The combination with a machine, including a frame, an actuated member, means on said machine to actuate said member, of a guard adapted to be reciprocated in front 50 of said actuated member, means to operatively connect said reciprocating guard and said actuated member, a swing guard at one side of said actuated member and an arm connected to said actuated member having means to lock said swing guard in its closed position and unlock said swing guard by the movement of said actuated member.

8. The combination with a machine, including a frame, an actuated member and means to actuate said member, of guard means to prevent the insertion of an operator's hand to the danger zone to said actuated member except for a single front opening during the rest period of said actuated member, said guard means including a movable

guard to sweep in front of and close said single opening to said danger zone and said guard means including guards between the sides of said movable guard and said machine and between the top of said movable guard and said machine, and locking means for one of said side guards adapted to release said side guard during the movement of said actuated member.

9. The combination with a machine, including a frame, an actuated member and means to actuate said member, of a guide mounted on said machine for horizontal adjustment, a guard mounted in said guide, means to operatively connect said guard and said actuated member to reciprocate said guard in said guide, said operative means adapted for adjustment between said guard and said member, means on said guard to connect said operative means for adjustment of the travel of said guard, a fixed guard at one side of said actuated member, a swing guard at the other side of said actuated member, a lock to fasten said swing guard in its closed position only during the rest period of 20 said actuated member and a bracket having a vertical adjustment to support said swing guard.

10. The combination with a machine, including a frame, an actuated member, a die carried by said member and means to actuate said member, of guards at both sides and above to enclose said die and leave only a single opening for the operator, a movable guard adapted to sweep in front of said opening during the movement of said die, geared means to operatively connect said movable guard and said actuated member, and locking means to fasten one of said side guards during the rest period of said actuated member and release it during the movement of said actuated member to allow for the removal of an operator's hand.

In witness whereof, I have hereunto set my hand.

MICHAEL J. McINTYRE.
